HOMOGENIZER

George J. Musgrave, Washington, D. C.

Application January 10, 1928. Serial No. 245,683

3 Claims. (Cl. 99-2)

This invention relates to a homogenizing valve and process of homogenizing cream and other liquids.

The primary object of the invention is to provide a device and method for first thoroughly breaking the globules contained in the liquid undergoing treatment and thereafter to subject the cream to a "molding" action to impart to the cream a high viscosity and uniform texture.

Another object of the invention is to provide a valve of tapering formation cooperating with a seat of complementary formation, which valve is adjustable in character to regulate the degree of pressure by which the cream is "molded".

Another object of the invention is to provide the molding valve with a corrugated extremity to break up the globules contained in the cream undergoing treatment before the same is subjected to a pressure to secure increased viscosity and a uniform product.

More specifically, the invention comprehends the idea of providing a terminal pin, as a continuation of the valve body, cooperatively arranged with the recess within the casing to insure proper alignment of the valve relative to the casing.

Numerous other objects and advantages of the invention will be apparent to those skilled in the art from a reading of the following specification in conjunction with the drawings attached hereto and forming a part hereof in which

Fig. 1 is a side elevation,

Fig. 2 is a cross sectional view,

Fig. 3 is a longitudinal section.

Referring now more specifically to the drawings, 1 represents the casing of the device having an inlet 2 and an outlet 3, and a central bore 4. Obviously the casing is secured to the cream conduit in any desired way. Attached to the upper end of the casing is a header 5 secured to the casing by screws 6, to which header is threadedly secured a cap 7 with an interposed packing 8 between the cap and the nipple 9 of the header. Mounted for reciprocatory movement in the bore of the casing 4, I provide a valve 10 of tapering formation corresponding substantially to the tapered formation of the bore 4 whereby to define a variable space 11 regulated by adjustment of the valve in a vertical direction. In the casing there are a series of ports 12 for permitting the treated cream to escape upwardly in the bore and through the outlet 3.

Preferably, as a continuation of the valve, I provide a portion 13 having a series of circum-

ferentially disposed corrugations 14 and serrations 15.

There is also provided a depending pin 16 for the valve which engages a corresponding recess 17 for properly centering the valve and maintaining it in correct symmetrical alignment with respect to the casing. The device also has an outlet 18 communicating with the recess 17 aforesaid and a valve 19 for securing proper drainage.

The valve 10 has secured thereto the stem 20 having the circumferential shoulder 21 and a block 22 fitted thereabove and secured to the valve by means of screws 23. Obviously, a rotary effort imparted to the stem 20 will secure the desired reciprocation of the valve.

It will be apparent that cream entering the inlet 2 will first be subjected to the action of the serrations and corrugations 14 and 15 respectively for thoroughly breaking up the fat globules contained in the cream, after which the cream emerges in the space defined by the casing and the valve where it is subjected to predetermined pressure to smooth it and increase its viscosity to the desired amount and impart to it a uniform texture.

I have found through commercial use of my invention that it obviates the formation of what are known in dairy practice as "cream plugs" which ordinarily result from devices providing too great a pressure or too small a pressure in accordance with the temperature of the cream. With the present device, no critical pressure is entirely necessary, which result I attribute to the action of first breaking the globules and thereafter molding them. Obviously, the pressure may be regulated according to the character of the cream and conditions to the viscosity desired.

A pump is secured to the outlet which causes the cream to be sucked into the inlet of the device, and by means of which pump the same cream is thereafter forced over the roughened or corrugated surface, where it is broken up into fine particles, after which it is forced into the molding chamber between the valve and casing where the fine particles are molded into a homogeneous mass by the pressure exerted between the walls. Ordinarily, the pumps employed with the device have three valves and consequently the sucking and pumping can take place simultaneously without interruption to the delivery of the homogenized body. The so-called "cream plugs" referred to above is a product resulting from incorporation of air into the butter fat and

so produces heavy butter fat which ordinarily in previous devices plugs the bottle opening.

It will be obvious to those skilled in the art that many changes may be made in my invention without departing from the spirit thereof as expressed in the following claims.

Having thus described my invention, what I claim is:

1. In a homogenizer, the combination with a casing having a bore therein, a reciprocatory valve mounted within the bore and spaced therefrom to provide means for receiving cream to be molded, said valve having a roughened surface for breaking up the fat globules previous to the introduction of the cream to the molding space.

2. A homogenized device comprising a casing having a bore therein, an inlet and an outlet for the cream, an adjustable valve within the bore and providing a molding space therebetween, said valve having at its lower extremity a roughened surface for breaking up the fat globules before the introduction of the cream to the molding space, means for adjusting the valve relatively to the casing to vary the pressure on the cream, and a downwardly extending pin provided

by the valve cooperating with the recess in the casing to center the valve relatively to the bore.

3. A homogenizing device comprising a casing having a bore of tapered formation therein, a valve of substantially corresponding formation fitting within the bore and adjustable to vary the space between the bore and valve, an inlet in the lower part of the casing, and an outlet in the upper portion thereof, a roughened surface for breaking up the fat globules located in proximity to the inlet and below the molding space, whereby the cream being forced through the device is first subjected to the roughened surface to break its fat globules and thereafter subjected to the pressure in the space between the valve and casing to mold the same, a recess within the casing and a centering pin terminating from the valve and mounted within the recess for centering the valve relatively to the casing to maintain a uniform circumferential space between the valve and casing, and a drain valve operable to discharge accumulated matter from the recess.
